UNITED STATES PATENT OFFICE

121,979

DESIGN FOR AN AUTOMOBILE GRILLE GUARD

Robert V. Morse, Ithaca, N. Y.

Application June 20, 1938, Serial No. 77,954

Term of patent 14 years

To all whom it may concern:

Be it known that I, Robert V. Morse, a citizen of the United States residing at Ithaca, in the county of Tompkins and State of New York, have invented a new, original, and ornamental Design for an Automobile Grille Guard, of which the following is a specification, reference being had to the accompanying drawing, forming a part thereof, in which

Fig. 1 is a side elevational view of an automo-

bile grille guard, the front end portion of an automobile being indicated by dot-and-dash lines to represent the relation of the grille guard thereto, and

Fig. 2 is a front elevational view of the grille guard showing my new design.

I claim:

The ornamental design for an automobile grille guard, as shown and described.

ROBERT V. MORSE.
